US0D1067235S

(12) **United States Design Patent** (10) **Patent No.:** **US D1,067,235 S**
(45) **Date of Patent:** **** Mar. 18, 2025**

(54) **DISPLAY PANEL**

(71) Applicant: **True Manufacturing Co., Inc.,**
O'Fallon, MO (US)

(72) Inventor: **Kevin Knatt**, St. Louis, MO (US)

(73) Assignee: **TRUE MANUFACTURING CO., INC.**,
O'Fallon, MO (US)

(**) Term: **15 Years**

(21) Appl. No.: **29/865,953**

(22) Filed: **Aug. 22, 2022**

Related U.S. Application Data

(62) Division of application No. 29/721,223, filed on Jan. 18, 2020, now Pat. No. Des. 976,905.

(51) **LOC (15) Cl.** **15-07**

(57) **CLAIM**

The ornamental design for a display panel as shown and described.

DESCRIPTION

FIG. 1 is a perspective view of a display panel;

FIG. 2 is a front view thereof;

FIG. 3 is a right-side view thereof;

FIG. 4 is a top view thereof;

FIG. 5 is a left-side view thereof; and,

FIG. 6 is a bottom view thereof.

The rear of the display panel forms no part of the claimed design. The broken lines in the drawings depict portions of the display panel that form no part of the claimed design.

1 Claim, 6 Drawing Sheets
